Inventor:
William A. Campbell

UNITED STATES PATENT OFFICE.

WILLIAM A. CAMPBELL, OF BELLEFONTAINE, OHIO.

HEATING-STOVE.

1,367,457.

Specification of Letters Patent. Patented Feb. 1, 1921.

Application filed August 27, 1917. Serial No. 188,340.

To all whom it may concern:

Be it known that I, WILLIAM A. CAMPBELL, a citizen of the United States, residing at Bellefontaine, in the county of Logan and 5 State of Ohio, have made a new plan for certain Improvements in Heating-Stoves Adapted to be used in Furnaces or in Ordinary Rooms, of which the following is a 10 specification of my furnace-stove, as set forth in application Serial No. 49,300, with additions thereto.

The object and nature of my furnace stove comprehends the utility for the great heat loss at the point of fuel combustion and 15 heated products, by means which absorb, deflect, radiate and circulate the effect for heating, and cooking purposes.

The specific nature of my invention in combination and detail of construction and 20 special arrangement of its parts will be hereinafter fully described and specifically pointed out in the appended claims and 25 illustrated in accompanying drawing, forming a part of the specification and application, in which the figures show the plan of the arrangement and connection of the parts and the letters of reference indicate the same throughout the drawings and specification.

Figure 1 is a vertical section of my furnace stove.

Fig. 2 shows a tubular hinge grate.

Fig. 3 illustrates the perforations and rim of the grate in which pipes are fitted thereto.

Fig. 4 is an elevation of the fuel chamber 35 showing the supporting apertures for the radial intakes of the cross-flue.

Fig. 5 is a top view of the furnace stove showing the plan of the heat off-takes and the cooking shelves.

Fig. 6 is the horizontal top view of the tubular cross flue.

Fig. 7 is a sectional top view showing the smoke in-take and off-take of the smoke flue.

Fig. 8 is a removable heat distributing 45 hood with discharging off-takes.

The fuel chamber wall is indicated by A composed of sections which are shown at a and a' . These sections have in their uniting edges semi circular openings indicated at a^2 50 which when joined form supporting apertures indicated at B in the fuel chamber wall for the passage and support of the radial intakes of the tubular deflecting crossflue, whereby it is centrally positioned within the 55 fuel chamber with the fire; a^2 indicates the

extension for fuel entrance; a^3 the door, and a^4 the hinge lugs for the grate, shown in Fig. 1.

The tubular deflecting cross flue indicated by C is formed of horizontal radial intakes 60 shown at c and a vertical off-take denoted by c^2 in Figs. 1 and 6 of the drawings. The function of this cross flue provides a large, deflecting and circulating heating means, it being positioned directly with the heat 65 source whereby it absorbs, deflects and radiates the heat effect to the rapid movement of the atmosphere therethrough.

The letter D indicates a superheating chamber formed with a receiving intake in 70 its bottom, shown at d , and the top open, the wall having a flanged edge denoted by d^3 and a register discharge at the top shown at d^4 . Cooking register shelves are indicated at d^5 in the upper portion of the 75 superheating chamber illustrated in Figs. 1 and 5 of the drawings.

This superheating chamber has three distinct functions of utility; it communicates with the discharge off-take of the crossflue; 80 it provides a large deflecting and radiating surface by its extended bottom and wall, which confines the heated products between its wall and the upper stove wall, shown at d^6 , causing the effects of the products of 85 combustion there around better radiation; and the upper portion of the interior chamber provides a warming and cooking means therein.

The letter E indicates the radiating smoke 90 flue of the stove top is formed by two concentric walls with its intake, denoted at e in the bottom in line above the fuel intake and with its offtake shown by e^1 positioned at the opposite diameter point from the intake in 95 flue wall as illustrated in Figs. 1, 5 and 7 of the drawings. The function of this flue is to prevent smoke escape at the fuel intake; and cause the movement of the heated products of combustion to pass from rear 100 to the front in the upper chamber of the stove; and producing greater radiating effect therefrom.

The letter F, indicates the peripheral 105 register off-take, whose function is to discharge the heated atmosphere from between the upper stove wall, G and the supplementary casing H . The said wall and casing is secured to the stove top by suitable means not shown. The letters h and h^1 indicate the 110

atmospheric intakes in the bottom of the supplemental casing; and the intake h^1 is adapted to be connected with other tubular intakes as need may suggest; h^2 indicates a heat distributing hood having discharging off-takes shown at h^3 illustrated in Fig. 8.

This removable heat distributing hood is adapted for furnace use, when suitably fitted to the upper peripheral surface of the stove 10 top (indicated by dotted lines in Fig. 1). The letter K indicates a hinged tubular or pipe grate formed by a circular perforated rim shown at k , and h^2 the hinge illustrated in Figs. 2 and 3 of the drawings, k^3 denotes 15 the hinge rod and h^4 the adjusting chain. The function of this grate provides greater durability, is easily repaired and permits the easy removal of clinkers or other obstructions. The letter L shows the ash pit 20 and l the door. Arrows indicate the heat and atmospheric movements.

This removable heat distributing hood indicated by Fig. 8, and by dotted lines in Fig. 1, of the drawing, is adapted for furnace use, when suitably fitted to the upper peripheral surface of the stove top, whereby the local heater having shelves may be converted into a furnace heater, from which the heated air may be distributed to remote 25 parts of the building.

From the foregoing description of my new furnace stove and illustrated in the accompanying drawings the principal and peculiar features of merit will be comprehended.

Having thus described my invention, what I claim and desire to secure by Letters Patent, is,—

1. In a furnace stove of the character described in combination with a stove wall, of a deflecting super-heating chamber formed with an intake in the bottom and the top open, the edge of wall flanged outwardly provided with a register and shelves within; 40 of a stove top formed with a ring shaped smoke flue wall and a peripheral register offtake, the smoke flue having the smoke intake in the bottom above the fuel intake and the discharge offtake oppositely disposed in 45 flue wall, said wall having a projecting rim in inner top which provides support for the flanged edge of said chamber wall and register thereon; of a deflecting radiating cross flue formed with horizontal radial intakes 50 and a vertical offtake; of a fuel chamber wall having supporting apertures formed therein, the said super-heating chamber having support and connection with the said stove top and with the offtake of the said cross flue, the radial intakes of the said cross flue having support and connection with the 55 apertures of the said fuel chamber wall, whereby the intense heat effect of the fuel combustion may be absorbed, radiated and circulated, as and for the purposes specified.

2. In a furnace stove of the nature described in combination with a stove and casing wall, of a stove top formed with a ring shaped smoke flue wall and a peripheral register offtake, the smoke flue having the intake in the bottom above the fuel intake and the discharge offtake oppositely disposed in 70 wall, said wall having a projecting rim in the inner top adapted to support the wall and register of super heating chamber; of a 75 deflecting super heating chamber formed with an intake in the bottom, the top edge of wall flanged outwardly, the top open provided with register and shelves within; of a deflecting cross flue formed with horizontal 80 radial intakes and vertical offtake; of a fuel chamber wall having supporting apertures formed therein, the said stove top having connection with a stove and casing wall and with the said super heating chamber wall, 85 the intake of the said chamber having support and connection with the offtake of the said cross flue and the radial intakes of it having support and communication with the supporting apertures of the said fuel chamber wall, whereby the heat effect of the fuel combustion may be used for the purpose set forth.

3. In a furnace stove of the character described in combination with a stove top, of a removable heat distributing hood formed with heat offtakes in the top and the bottom an open intake; of a stove top formed with ring shaped smoke flue wall and a peripheral register heat offtake, the flue having the 90 smoke intake in the bottom above the fuel intake, and the smoke offtake oppositely disposed in the flue wall, the said hood having secured connections with the said stove top, whereby the local heater may be converted 100 into a furnace heater from which the entire heated air may be distributed to remote parts, as specified.

4. The herein described furnace stove, comprising the following elements, in combination with a stove and casing wall; of a fuel chamber having supporting apertures formed in the wall; of a deflecting and radiating cross flue formed with horizontal 110 radial intakes and vertical offtake; of a deflecting super heating chamber having an intake in the bottom, the top open and the edge of wall flange and provided with a register; of a stove top formed with a ring shaped smoke flue and peripheral register offtake the said flue having the smoke intake in the bottom above the fuel intake and the smoke offtake oppositely disposed in flue wall, said wall having a projecting rim in the inner top adapted to support the 115 flange edge of the super heating chamber wall and register; of a removable heat distributing hood formed with offtakes in the top and the bottom an open intake; the said hood having secured connection with the 120 flange edge of the super heating chamber wall and register; of a removable heat distributing hood formed with offtakes in the top and the bottom an open intake; the said hood having secured connection with the 125 flange edge of the super heating chamber wall and register; of a removable heat distributing hood formed with offtakes in the top and the bottom an open intake; the said hood having secured connection with the 130 flange edge of the super heating chamber wall and register.

said stove top which top having connection with the said open discharge of the said super heating chamber, stove and casing wall, the intake of the said chamber having 5 support and connection with the offtake of the said cross flue, and the radial intakes of the said cross flue having support and communication with the supporting apertures of the said fuel chamber wall, whereby the

heat effect of the fuel combustion may be 10 utilized for the purposes specified.

In testimony whereof I affix my signature to said specification and claims in presence of two witnesses.

WILLIAM A. CAMPBELL.
